APPARATUS FOR REDUCING NOISE IN
MICROPHONE CIRCUITS

Joseph Frank Andrews, New York, N. Y.

Application February 26, 1944, Serial No. 523,993

1 Claim. (Cl. 179—1)

(Granted under the act of March 3, 1883, as
amended April 30, 1928; 370 O. G. 757)

1

This invention relates to microphone or speech input circuits of communication systems and has particular reference to radio communication systems for aircraft.

In currently designed aircraft communication systems of the class described and particularly where oxygen mask equipment is utilized, much distortion of speech in the receivers has been found to exist. This distortion is caused primarily by too high an amplification of the lower frequency bands of speech frequency components. The components of speech frequency in the lower bands i. e. those below about 350 cycles, approach the natural resonant frequency of the various voice cavities which include the voice passages of the throat and the cavities in the oxygen mask. Because of this, sympathetic vibration of such cavities at their natural resonant frequency is set up and fed into the speech amplifier at too high an amplitude level and thereby produce distortion in the speech when it is received. Furthermore, certain other low frequency noises which are inherent in the operation of the aircraft find their way into the speech amplifier to produce additional distortion. Also present are high frequency noises i. e. those above about 3,000 cycles, and these likewise are also stepped up to too high a level in the speech amplification and interfere with intelligibility of the speech as it is received.

Since the naturalness of one's voice is determined primarily by those components of speech frequency which lie between about 350 and 3,000 cycles, and which may be referred to as the essential voice frequency band, it is evident that much of the aforesaid distortion can be eliminated by providing a system in which frequencies below and above the aforesaid limits are substantially attenuated.

The primary object of this invention is therefore to provide a novel microphone input circuit for communication systems in which substantial attenuation is obtained with respect to frequencies which lie below and above predetermined limits.

A more specific object of the invention is to provide an input circuit of the class described which comprises a series connected capacitor and a parallel connected varistor having a capacitor in series therewith, the function of which is to substantially attenuate frequencies which lie both above and below predetermined limits.

These and other objects will become more apparent from the detailed description to follow and from the accompanying drawing, the single

figure of which is a schematic circuit diagram of a preferred embodiment of the invention.

Referring now to the drawing, the speech input circuit includes a microphone 10 which is connected in circuit with a battery 11 and primary winding 12 of step-up transformer 13.

The secondary winding 14 of transformer 13 is connected at one side thereof to the grid 15 of amplifier tube 16. The other side of the secondary winding 14 is connected to the cathode 17 of tube 16.

The anode 18 of tube 16 is connected in circuit with a source of potential 19 and the primary winding 20 of step-up transformer 21. The secondary winding 22 of transformer 21 is connected to other amplification stages if desired and thence fed into the telephone receivers. Such parts of the circuit are conventional and hence have not been illustrated as the invention described and claimed herein is directed to novel improvements in that portion of the speech input circuit which is shown in the drawing.

A capacitor 23 is connected in series in the speech input circuit and is of such capacity as to present a very high impedance to frequencies below about 350 cycles but which decreases toward the normal impedance within the essential voice frequency band which lies above this frequency. Thus the gain of tube 16 is reduced materially with respect to speech frequency components below 350 cycles.

Connected in parallel with the secondary 14 of transformer 13 is a second capacitor 24 and a varistor 25 in series therewith. Varistor 25 has a negative resistance characteristic. One suitable type which may be used is made from silicon carbide and is described in the October 1940 issue of the Bell Laboratory Record. The resistance characteristic of the varistor is such that

its value decreases exponentially as the potential impressed across it is increased. Thus a very small change in the potential impressed across the varistor will result in a considerable change in current through it. The function of varistor 25 and capacitor 24 in series therewith is to present a high shunt impedance to all components of speech frequencies below about 3,000 cycles.

However, with respect to frequencies which lie above 3,000 cycles and which are normally at too high a level of signal potential, the impedance presented by capacitor 24 and varistor 25 drops appreciably and hence increases the shunting effect of capacitor 24 to reduce the gain of tube 16.

A parallel connected resistor 26 may also be

utilized and functions to furnish grid bias to tube 15.

While the proper values of capacity and resistance of the various parts shown in the drawing will vary somewhat with the type of microphone, transformers and amplifier tubes used in the system, I have found that very good results may be obtained when the capacity of capacitor 23 is .025 mf., that of capacitor 24 .008 mf., the resistance of varistor 25 variable between 1,000, 10 and 10,000 ohms, and the resistance of resistor 26 2 megohms.

In conclusion, it should be evident that the novel circuit arrangement which has been described will function to attenuate substantially those voltages impressed across the grid 15 of amplifier tube 16 which are produced by frequencies which lie below about 350 cycles and above about 3,000 cycles with the result that speech input to the amplifier tube 16 from the microphone 10 is amplified and transmitted to the various receivers in the system with very little distortion.

The invention described herein may be manufactured and used by or for the Government of the United States of America for governmental purposes without the payment of any royalties thereon or therefor.

Having thus fully described my invention, I claim:

In an improved distortionless communication

apparatus used with an oxygen mask for attenuating sounds impinging on a microphone therein, which sounds have a high magnitude at frequencies above and below the essential speech frequency band, the combination of a circuit for use with such apparatus including a first capacitor of such size as to offer a high impedance to frequencies of the order of 350 cycles and below, means having a negative resistance characteristic, said means being in series with a second capacitor, said means and said second capacitor being in shunt across said circuit for effecting a low impedance and hence increased shunting effect to signals of high magnitude at frequencies of the order of 3000 cycles and above, whereby the output of the circuit has an essentially flat frequency response within the speech frequency band.
